STAPLE REMOVER

John A. Yerkes, New York, N. Y.

Application June 12, 1945, Serial No. 599,650

9 Claims. (Cl. 254—28)

1

This invention relates to a staple pulling device for removing staples engaged in material such as letters, papers, laminated sheets, wood, and the like, by conventional office stapling machines.

One of the objects of the invention is to provide a staple puller or remover which will be rugged, inexpensive, easy and convenient to operate, and of foolproof construction.

Another object is to provide a staple remover which upon a continuous gripping or operating movement will first engage the pulling jaws with the staple without damage to the stapled material and then with the same gripping actuation secondarily lift the staple out of the material, one jaw maintaining its engagement with the material while the other lifts the staple.

Another object of the invention is to provide a device which will uniformly withdraw both legs of the staple at the same time.

Another object of the invention is to provide a staple pulling device which may be operated by holding in the hand or by placing on the table.

These and other objects of the invention will become apparent from the following description and drawings which are merely exemplary.

Figure 1 is a perspective view of the staple remover showing operation when held in the hands.

Figure 2 is a cross sectional elevation of the device when at rest.

Figure 3 is a bottom view of Figure 2.

Figure 4 is a fragmentary sectional view taken along the line and in the direction 4—4 of Figure 2.

Figure 5 is a fragmentary sectional view taken along the line 5—5 of Figure 2 showing the relation of the staple and lifting jaw before the device is operated.

Figure 6 is a fragmentary sectional elevation showing the relation of the parts at the end of the primary movement after the jaws have been inserted under the staple.

Figure 7 is a fragmentary sectional view taken along the line 7—7 of Figure 6.

Figure 8 is a fragmentary sectional elevation showing relation of the parts at the end of the secondary movement after the lifting jaw has completely removed the staple from the material.

Figure 9 is a fragmentary sectional view taken along line 9—9 of Figure 8.

Figure 10 is a fragmentary sectional view generally similar to Figure 9 with the exception that the jaws have not completed their movement relative to each other and one leg has not be-

2

come unclinched which is the start of a one-leg withdrawal condition.

Figure 11 is similar to Figure 10 except that the jaws have completed their movement and the staple has been withdrawn completely.

The preferred embodiment to best illustrate the invention will be described.

Referring to Figures 1 and 2, a rocker arm or grip member 1 is preferably made of thin metal and formed in the shape of an irregular U substantially as shown in Figures 1 and 2. A portion of said arm forms a rounded protuberance 7 suitable for manual gripping by the hand as seen in Figure 1. Another portion consists of a depending arm or portion 8 at the extremity of which the metal is bent outwardly, substantially at right angles to the axis of arm 8, to form retaining means 6. Secured to arm 8 by any suitable means, such as by rivet 9, is hardened lifting jaw 2, said jaw 2 being bent into the form of an angle plate for convenience of fastening but it may be of any other convenient form or may be an integral part of arm 8. The operating end of jaw 2 is preferably slightly beveled as at 10 (Fig. 6) to facilitate inserting said jaw under the bridge of a staple. The lower face of retaining means 6 is spaced from the upper face of lifting jaw 2 to form a space 11. The height of the space or notch-like aperture, that is to say, the distance separating said faces should be sufficient to permit easy entry of the bridge of a staple but should not be large enough to permit withdrawal of one leg only as will be explained hereafter.

Grip member 1 is pivotally connected to link 12 by means of rivet pin 13 which passes through suitable holes in said grip member and said link, said link 12 being preferably of relatively heavy section and nested closely between the interior walls of grip member 1 so as to give a sliding fit relationship.

Link 12 is bored at its lower end for the reception of rivet pin 14 which also extends through suitable holes in a housing 15. Housing 15 may be roughly rectangular in form with two parallel side walls 16, a front wall 17, a rear wall 18, and a floor 19 which is preferably shaped to form finger-grips 21 (Figure 2). Said grips 21, however, may be omitted, for "on-table" operation, as described hereafter. The upper portion of housing 15 is left open, for the partial reception of grip member or rocker arm 1, a portion of which is closely nested between the side walls 16 of housing 15, the members being in sliding fit relationship.

Side walls 16 are cut away to form an opening 22 which enables the operator to see the jaws 2 and 3 in operation.

Guard or anvil jaw 3 is secured to front wall 17 by any suitable means such as rivet 23. Said jaw is preferably of hardened metal and is shaped to form a pair of prongs 24 and 25 (Figure 3) which are pointed and slightly sloped to facilitate their entry between the bridge of a staple and the material engaged by the staple. Prongs 24 and 25 may be raised as at 26 and 27 to form a pair of abutments for limiting the relative movement between the prongs and the staple, but such abutments are not essential to the operation. The jaw 3 may be integral with the frame if desired although the form shown is preferable.

A leaf spring 28 is secured to link 12 by any suitable means such as by a screw 29 or a drive pin. As will be explained in the description of the operation of the invention, leaf spring 28 functions as two separate springs, the upper half 30 acting between link 12 and grip member 1, the lower half 31 acting between link 12 and housing 15.

An abutment pin 32, secured to housing 15 by riveting or the like, serves to limit the forward (or counterclockwise) movement of link 12 which is urged forward by lower half 31 of spring 28.

Similarly secured to arm 8 of grip member 1 is a guide pin 33 extending through an arcuate guide-slot 34 formed in housing 15 and shaped substantially as shown in the Figures 1, 2, 6, and 8. The use of said pin 33 and said guide-slot 34 is not essential to the operation of the device but is desirable for maximum smoothness of operation.

An abutment pin 35 secured to grip member 1 serves to abut against link 12 at the end of the primary movement hereafter described.

For purposes of facilitating explanation of the operation of the device, reference will be made to a. the primary, first, or engaging movement, and b. the secondary, second, or lifting movement. Both movements are obtained by the simple act of urging grip member 1 or rocker arm 14 farther into housing 15, either by a simple gripping action as shown in Figure 1, or by setting the device on the stapled material and simply depressing arm 1, the latter procedure being known as "on-desk" operation.

Referring to Figures 1 and 2, jaws 2 and 3 are pressed firmly against stapled material 18, with the bridge 38 of staple 5 positioned between the normally parted jaws.

In the primary or engaging movement, grip member 1 is depressed until pin 35 abuts link 12. Upper half 30 of spring 28 yields under the pressure but lower half 31 is unaffected and link 12 remains motionless. Thus, grip member 1 and its extension 8 are caused to pivot clockwise (Figures 2 and 3) on motionless link 12, and the relative movement of jaws 2 and 3, toward each other and under the bridge of the staple is completed, as shown in Figure 6. Prongs 24 and 25 of guard jaw 3 and also lifting jaw 2 have now been forced between the bridge of the staple and the stapled material. As shown in Figure 7, the space between prongs 24 and 25 is sufficiently wide to permit passage of lifting jaw 2 between said prongs. As may be seen in Figure 7, staple legs 36 and 37 are not, as yet, clinched; at the end of the primary or engaging movement, the relatively thin jaws having been permitted to enter beneath bridge 38 by a slight yielding and spring in the staple. There may be a slight move-

ment of the staple legs in the material but it is insubstantial relative to the actual and complete removal movement. The actual withdrawal and unclinchng of the staple occurs in the secondary or lifting movement to the position shown in Figures 8 and 9.

As previously stated, at the end of the primary or engaging movement, pin 35 on rocker arm 1 abuts link 12 and as additional downward pressure is applied on grip member 1, both member 1 and link 12 are locked together (Figure 6) and pivot in unison around rivet pin 14 secured to housing 15 in a clockwise direction to the position of Figure 8. Lower half 31 of spring 28 yields to permit the pivotal movement just described. Lifting jaw 2 is raised (Figure 8) pulling bridge 38 of staple 5 with it. Legs 36 and 37 of said staple are caused to straighten without injury to the stapled material because throughout the entire secondary or lifting movement, guard jaw 3 remains in contact with the stapled material 18 and legs 36 and 37 are straightened or "ironed-out" by being pulled past prongs 24 and 25.

From the description of the operation thus far, it should be apparent that during the primary or engaging movement, since lifting jaw 2 and guard jaw 3 are both forced under the staple bridge 38 simultaneously from opposite directions and with substantially equal forces, the staple will remain in fixed position relative to the stapled material. Thrusting only one jaw under the staple bridge may cause tearing of the stapled material if the strength of said material is inadequate in view of the force required to cause the jaw to enter beneath the staple bridge, thin paper being, for example, especially liable to injury.

The use of opposing jaws for engagement, together with the simple lifting action of the secondary movement obtains an effective easily-operated structure which avoids injury to the most delicate material.

It should be noted that rivet pin 13 is normally positioned substantially directly above staple 5 (Figure 6) and rivet pin 14 is positioned as close as practical to the stapled material, thus the movements of the jaws in the primary movement and of the lifting jaw in the secondary movement are in the path of as flat an arc as is practicable, closely simulating straight-line motion.

Retaining member 6 is for the purpose of preventing single leg withdrawal, or one wherein only one leg is withdrawn, the other remaining clinched to the material. Such a withdrawal is not satisfactory and may result in tearing of the material. In some instances, one staple leg is more firmly clinched than the other which will cause single-leg withdrawal. The start of such a condition is seen in Figure 10.

Retaining member 6 is spaced from the upper surface of lifting jaw just enough to permit easy entry of the bridge of the staple. In the event one leg only yields, the bridge will tend to become cocked in the space between the lifting jaw and the retaining member, as seen exaggerated in Figure 10. When this occurs, the bridge will become gripped so that the wire of the staple cannot slip through the space or notch-like aperture defined by the upper surface 40 (Fig. 10) of the lifting jaw and the lower surface 41 of the retaining member 6. The bent portion 42 of the staple also will come into contact with the restricted space between the lifting jaw 2 and the retaining member 6 which further will prevent

passage of the wire therethrough. As seen in Figure 10, the leg 43 of the staple has remained clinched after the leg 44 has become unclinched. This will cause the bridge 38 to become cocked in the restricted space between the retaining member 8 and the lifting jaw 2 so that the staple wire will be gripped thereby and not be pulled through so as to leave the staple and one leg in the material, or to mutilate the same. In Figure 11, leg 43 is shown as having been unclinched as the jaws are moved further apart, the staple bridge having been gripped so that both legs have been withdrawn. The staple will in this manner be withdrawn uniformly from the material by the gripping action of the retaining member and lifting jaw when the single-leg withdrawal first starts.

The height of the notch-like aperture or distance between the upper face of the lifting jaw and the lower face of the retaining member should be made substantially that of the maximum size staple to be pulled, sufficient clearance being allowed so that the staple bridge enters with ease. The variation in diameter of staple wires used for practical purposes is such that a height to accommodate the largest will operate satisfactorily with most of the sizes now employed.

If the space is considerably greater than the diameter of the wire, a member placed on the lifting jaw will serve merely as a means to prevent the liberated staple from flying violently away from the removal jaw and not as a retaining member to grip the wire and prevent the same from being drawn through the notch. The retaining member preferably should extend a substantial distance longitudinally of the bridge of the staple, such as seen, for example, in Figure 7. By use of the retaining member as described, the gripping effect is applied only when needed and upon freeing of the staple from the material, the gripping is no longer effective, thus allowing the staple to be easily freed from the device by a slight shake without the necessity for manually forcing the staple out.

The principles involved and device also may be used for pulling tacks and the like by the simple expedient of specifically shaping the jaws to suit the article to be removed.

It should be understood that various changes and modifications may be made from those specifically illustrated without departing from the spirit of my invention or the scope of the appended claims.

I claim:

1. A staple pulling device including a pair of jaws having tip portions movable to overlapping positions relative to each other, means to primarily move said both jaws relatively toward each other in overlapping relationship, both jaws moving under the bridge of a staple engaged in material, and means for thereafter secondarily moving one of said jaws relative to the other jaw in a direction differing from said primary movement to raise said staple and remove the same from the material in which said staple is engaged.

2. A staple pulling device including a pair of jaws, jaw operating means movable relative to each other and connected with said jaws to first move said jaws relatively toward each other under the bridge of a staple engaged in material, and means connected with said jaw operating means to thereafter move one only of said jaws substantially perpendicularly relative to said

other jaw and said material as said jaw operating means is moved further following said primary movement to remove said staple from said material.

- 5 3. A staple pulling device including a guard jaw and a lifting jaw having tips movable into overlapping relationship, an operating means for said jaws, means connected to said operating means to primarily move said jaws relatively toward each other under the bridge of a staple engaged in material with insubstantial movement of said staple out of said material as said operating means is operated, both of said jaws being under said bridge and the tips thereof being in overlapped relation, and a second means connected with said operating means for secondarily moving said lifting jaw away from said guard jaw in a direction differing from said primary movement of said jaws to raise said staple and remove the same from the material, said guard jaw being adapted to remain adjacent said material.
- 10 4. A staple pulling device including a pair of jaws having tips movable into overlapping relationship, jaw operating means movable relative to each other to primarily move said jaws relatively toward each other under the bridge of a staple engaged in material without removal to any substantial extent of said staple out of said material, both jaws moving under said staple, and means connected with said jaw operating means for secondarily moving one of said jaws away from the other jaw and the material as said jaw operating means are moved relative to each other after said primary movement, said other jaw remaining adjacent said material, the direction of said secondary movement being substantially at right angles to said primary movement to remove said staple from said material.
- 15 5. A staple pulling device including a pair of jaws having tips movable into overlapping relationship, operating means connected with said jaws and movable relative to each other to first move said jaws relatively toward each other and under the bridge of a staple engaged in material, the tips of said jaws moving past each other in overlapped relationship a greater distance than the thickness of the staple, means connected with said operating means and movable thereby for thereafter moving in a different direction than said first movement one of said jaws relative to the other one of the jaws to remove said staple from said material, and an engaging member on said last mentioned jaw for closely engaging the bridge of said staple to effect uniform withdrawal of both staple legs as said staple is removed.
- 20 6. A staple pulling device including a guard jaw and a lifting jaw for simultaneous insertion from opposite directions under the bridge of a staple engaged in material with their tips in overlapping relationship at least the thickness of the bridge of a staple to be removed, said jaws being first movable relatively toward each other, means for raising said lifting jaw relative to said guard jaw in a direction different than the insertion movement of said jaw to remove said staple from said material, and a retaining means positioned over the lifting jaw and spaced therefrom at least the thickness of a staple but limited to a confined space for gripping a bent portion of the staple, whereby said staple is withdrawn uniformly.
- 25 7. A staple pulling device comprising a pair of staple pulling jaws, a pair of operating grips movable relative to each other, means connecting said staple pulling jaws with said grips, connecting said means between said grips for first moving said

jaws relatively toward each other under the bridge of a staple engaged in material, and means co-operating with said connecting means after said first movement of the jaws to cause continued movement of said grips in the same relative direction to move one of said jaws relative to the other in a different direction than the first movement of said jaws for withdrawing said staple from said material.

8. A staple pulling device including a frame, a grip member movable relative to said frame, a link pivotally mounted on opposite ends thereof to said frame and grip member respectively, a guard jaw carried by said frame, a lifting jaw carried by said grip, a stop to limit pivoting movement of said grip on said link, a spring mounted between said frame and grip member and urging the same apart, said spring also being connected to said link and restraining rotation of said link until said stop has become operative, pivoting movement of said grip on said link moving said jaws relatively toward each other and pivoting movement of said link on said frame raising said lifting jaw relative to said guard jaw.

9. A staple pulling device including a frame, a grip member movable relative to said frame, said frame and grip having an interconnecting pin

and slot motion guiding means, a link pivotally mounted on opposite ends thereof to said frame and grip member respectively, a guard jaw carried by said frame, a lifting jaw carried by said grip, a stop to limit pivoting movement of said grip on said link, pivoting movement of said grip on said link moving said jaws relatively toward each other under the bridge of a staple and pivoting movement thereafter of said link on said frame raising said lifting jaw relative to said guard jaw.
